(57) **CLAIM**

We claim the ornamental design for a flower-shaped balloon weight, as shown and described.

DESCRIPTION

FIG. 1 is a front elevational view of the flower-shaped balloon weight in accordance with this invention;
FIG. 2 is a right side elevational view thereof, the left side elevational view being a mirror image;
FIG. 3 is a rear elevational view thereof;
FIG. 4 is a top plan view thereof; and,
FIG. 5 is a bottom plan view thereof.
